UNITED STATES PATENT OFFICE.

DANIEL R. PORTER, OF REVERE, MASSACHUSETTS.

HORSESHOE.

SPECIFICATION forming part of Letters Patent No. 308,926, dated December 9, 1884.

Application filed March 29, 1884. (No model.)

To all whom it may concern:

Be it known that I, DANIEL R. PORTER, of Revere, county of Suffolk, State of Massachusetts, have invented an Improvement in 5 Horseshoes, of which the following description, in connection with the accompanying drawings, is a specification, like letters on the drawings representing like parts.

That part of a horse's foot called the "frog" 10 is very elastic, and when the foot is in its natural or unshod state the frog comes directly against the ground, the whole weight of the horse thus coming upon the same when walking or running. The frog, subjected to 15 such pressure, is expanded, and expands the hoof at its heel, or works the foot, thus keeping the same in healthy condition, and especially avoiding contraction of the heel, which produces lameness. When a metal shoe is 20 nailed upon the foot, and the roads are good or smooth, the frog seldom touches the ground, and consequently it does not receive the blow caused by the horse striking his foot against the ground, as was intended, and the frog, not 25 being worked, fails to keep in proper healthy condition, and fails to act to expand the heel of the constantly-growing foot. To obviate this contraction of the heel, and work the frog as intended by nature, I have provided 30 the heel of the shoe with a frog-worker, the same being shown as a metal bar loosely connected with the shoe, located between it and the foot at its heel, extended across the frog and rising and falling with relation to the heel 35 of the shoe at each step, the movement of the frog-worker being away from the shoe when the shoe strikes the ground, wedge-shaped projections on the frog-worker then acting in the spaces between the sides of the frog and 40 the inner wall of the hoof, exerting such strain or pressure on the foot as will tend to expand it at the heel.

Figure 1 in perspective represents the upper side of a horseshoe with a frog-worker placed thereon. Fig. 2 shows the frog-worker removed. Fig. 3 is an end view of Fig. 1, looking in the direction of the arrow thereon.

The shoe S, of usual shape and material, is provided at its heel with holes h, as shown in 45 dotted lines in Fig. 3, to receive the studs b, attached to the under side of the wedge-shaped

ends w of the frog-worker F, the main body of which fits into the space between the ends of the shoe at the heel, as shown in Figs. 1 and 3, the outer face, 2, of the frog-worker coming 55 substantially level with the outer face of the shoe at the heel, but the inner side, 3, of the frog-worker will preferably be made, as shown, to fall in a plane lower than that of the upper side of the shoe at the heel. The frog-worker 60 is laid upon the foot against the frog, with the wedge-shaped projections w in the spaces at the side of the frog and between it and the inner side of the wall of the hoof, the said space being slightly cleaned out, and then the 65 shoe is laid upon the foot, the holes h receiving the studs b, and the shoe is nailed in place as usual. When the horse puts his foot upon the ground, the frog-worker also strikes the ground, and as the weight of the horse settles 70 on the foot the frog-worker is moved away from the shoe, the studs b sliding in the holes h, such movement of the frog-worker causing the frog to be pressed as in walking, and enabling the wedge projections w, as they enter 75 the said spaces, the frog then yielding, to exert such strain or pressure on the foot as will tend to cause the same to expand at the heel, or to obviate heel contraction and keeping the foot in healthy condition.

I am aware that the heels of horseshoes have been provided with cross-bars to connect them positively together.

I claim—

1. A horseshoe combined with an independently-movable frog-worker applied to the heel of the shoe, to operate substantially as described.

2. The shoe provided at its heel with holes h, combined with the frog-worker having 90 studs b, and provided with projections w to enter the spaces between the sides of the frog and the inner wall of the foot, substantially as described.

In testimony whereof I have signed my name 95 to this specification in the presence of two subscribing witnesses.

DANIEL R. PORTER.
